(57) **CLAIM**

The ornamental design for femoral prosthesis, as shown and described.

DESCRIPTION

FIG. 1 is a side elevation of a femoral prosthesis showing our new design;

FIG. 2 is a side elevation of the side opposite shown in FIG. 1;

FIG. 3 is an end elevation thereof;

FIG. 4 is an end elevation of the end opposite shown in FIG. 3;

FIG. 5 is a front perspective view thereof, shown on an enlarged scale;

FIG. 6 is a top plan view thereof; and,

FIG. 7 is a bottom plan view thereof.
